(57) **CLAIM**

The ornamental design for a device for squeezing a tube as shown and described.

DESCRIPTION

FIG. 1 is a top perspective view of a device for squeezing a tube showing the new design;

FIG. 2 is a bottom perspective view thereof;

FIG. 3 is a front view;

FIG. 4 is a top view;

FIG. 5 is a rear view;

FIG. 6 is a bottom view;

FIG. 7 is a left side view; and,

FIG. 8 is a right side view.

The surface shading is intended to depict surface contour and forms no part of the claimed design.

1 Claim, 5 Drawing Sheets
